G. G. ROBERTS.
BOTTLE CASE.
APPLICATION FILED MAY 16, 1911.

1,022,971.

Patented Apr. 9, 1912.

UNITED STATES PATENT OFFICE.

GEORGE G. ROBERTS, OF TOLEDO, OHIO.

BOTTLE-CASE.

1,022,971.

Specification of Letters Patent.

Patented Apr. 9, 1912.

Application filed May 16, 1911. Serial No. 627,634.

To all whom it may concern:

Be it known that I, GEORGE G. ROBERTS, a citizen of the United States, residing at Toledo, in the county of Lucas and State of Ohio, have invented certain new and useful Improvements in Bottle-Cases, of which the following is a specification.

This invention relates to bottle shipping cases and has for its object the provision of 10 a case or crate of simple and durable construction by the use of which bottles may be transported without liability to breakage, and in which the cover will be held to the body of the case or crate by simple means 15 which will prevent the detachment of the cover but will permit it to be swung entirely clear of the body or case when it is desired to remove and insert the bottles or other articles.

20 The invention also seeks to provide a device for the stated purpose which will be so constructed that breakage of the several parts will be reduced to a minimum and the life of the box or crate correspondingly 25 prolonged.

In the accompanying drawings, which fully illustrate the preferred embodiment of my invention, Figure 1 is a plan view of a crate constructed in accordance with my improvement and showing the lid or cover in the open position. Fig. 2 is a vertical section on the line 2—2 of Fig. 1, showing the cover in the closed position in full lines and indicating by dotted lines the open position 35 thereof. Fig. 3 is an enlarged detail section through one of the bottle retaining pins or pegs. Fig. 4 is an enlarged detail section taken horizontally through one corner of the crate. Fig. 5 is an enlarged detail view 40 of one edge of the cover. Fig. 6 is a detail perspective view of the upper member of the connection between the lid and the body. Fig. 7 is a similar view of the lower member of the connection.

45 In carrying out my invention, I employ a preferably rectangular crate or case which is constructed of wooden sides and ends designated as 1 and 2, respectively, and a bottom preferably composed of wooden slats 50 3 connected by tongue and groove joints and partly cut away to provide slots 4 to effect ventilation. In the end walls 2 are provided openings or slots 5 which may be utilized as handles, and in the front side 1, near the 55 upper edge of the same, is an opening 6

through which a sealing wire may be passed. The cover 7 is also preferably constructed of wood and is provided near its front edge with an opening 8 to receive the sealing wire passed through the opening 6 in the front 60 wall of the crate so that the lid will be held in its closed position during shipment, as will be readily understood.

Within the case or crate, at the ends thereof, I provide fixed guides or retainers 9 65 which are shown as made of strap iron but may be of heavy wire, and are secured to the end walls of the crate. These guides or retainers pass rearwardly and upwardly to the rear wall of the crate and are provided 70 at their rear ends with slots or openings 10. On the under side of the cover, at the ends thereof, I secure the slides or runners 11 which are preferably metallic straps passing through the slots 10 and having their 75 front ends turned upward and secured to the lid, as clearly shown. The rear ends of the runners are bent upward past the rear edge of the lid and over upon the top of the same where they are secured. The rear 80 ends of the guides project through notches 12 in the upper edge of the back wall of the body of the crate and the runners play through said notches.

It will be seen from the description thus 85 far given, taken in connection with Fig. 2 of the drawings more particularly, that the cover may slide horizontally upon the box or crate, and will rest directly upon the upper edges of the sides and ends thereof, the 90 runners and guides being arranged at the ends of the crate so that they will not be apt to break any of the bottles in the case and will not take up space which may be utilized for bottles. The rearward movement of the 95 cover will be arrested by the engagement of the upturned front ends of the runners with the stops presented by the rear ends of the guides, whereupon the cover may swing about the said rear ends of the guides as a 100 center and assume a vertical position in rear of the box, as indicated in dotted lines in Fig. 2, the engaging guides and runners aiding in the support of the cover.

In the upper and lower faces of the cover, 105 at the end edges thereof, I form shallow recesses 13 and in the said recesses I secure the upper and lower flanges 14 of a U-shaped reinforcing and wear strip 15 which passes around the end edges of the cover so as to 110

prevent warping or splitting thereof. The corners of the body of the case are reinforced by metallic angle-plates having outside flanges 16 fitted in shallow recesses 17 in the outer faces of the front and rear walls, from which flanges 16 the angle plates extend across the end edges of the side walls, as shown at 18, and then pass inward between the inner faces of the side walls and 10 the end edges of the end walls, as shown at 19, the inner edges or extremities of the said angle-plates being bent against the inner faces of the end walls, as shown at 20. Headed nails or other fastenings 21 are inserted through the parallel flanges or members 16 and 19 and through the ends of the side walls into the end walls, so as to secure the members together, and it will be observed that by the construction shown and 20 described I provide two metallic bodies through which these fastenings are driven so that an exceedingly strong corner joint is formed. It will also be noted that the corner reinforcing angle-plates are disposed 25 vertically so that their ends are presented to the end faces of the channel strips secured to the edges of the cover and that when the cover is swung into a vertical position in rear of the body the turning or sliding 30 movement will occur between two metallic surfaces and consequently wear upon the wooden body of the crate or case is overcome.

The bottles or other articles are held 35 within the crate by being fitted between pins or pegs 22 rising from the slatted bottom and spaced apart at suitable intervals to accommodate the bottles or other articles to be shipped, it being understood that the 40 shipping case will be furnished in a variety of sizes according to the particular demands of the user. The lower ends of the pins or pegs are reduced and these lower reduced extremities have formed therein threads 23 45 adapted to engage internally threaded openings in the bottom of the crate or case so that the pegs can not readily pull out of place, while at the same time they may be readily removed and inserted during the 50 course of manufacture or to make necessary repairs. In order to still further reinforce the crate and to guard against accidental removal of the pins or pegs, metallic strips 24 are disposed longitudinally upon the under 55 sides of the slats 3 within shallow grooves 25 formed therein, and small screws 26 are driven upwardly through these reinforcing strips into the ends of the pegs, as clearly shown in Fig. 3.

60 It will thus be seen that I have provided an exceedingly strong construction by which the pegs will be held firmly in place and should any one peg be broken through extraordinary or careless usage it may be 65 quickly removed and replaced with a new

pin without necessitating the provision of an entirely new crate. Furthermore, the particular manner of securing the pins or pegs shown and described by me, will prevent splitting of the pegs in placing them in position, and an exceedingly durable case will be provided. 70

Having thus described my invention, what I claim and desire to secure by Letters Patent is:

1. In a bottle-shipping case, the combination of a body, stationary guides secured to the inner faces of the end walls of said body and having transverse slots at their rear ends, a cover adapted to rest on the upper edges of the body, and runners secured to and depending from the cover and slidably engaging the transverse slots in the guides. 80

2. In a bottle-shipping case, the combination of a body, stationary guides secured to the inner faces of the end walls of the body and projecting over the rear wall of the same, a cover adapted to rest upon the upper edges of the body, and runners secured to said cover and fitting within the body, said runners slidably engaging the projecting portions of the guides and adapted to form a hinged connection therewith. 90

3. In a shipping case, the combination of a body having notches in the upper edge of its rear wall, stationary guides secured within the body in alinement with said notches and projecting thereinto, and a cover adapted to rest upon the body and provided with depending runners slidably playing through said notches and slidably engaging the guides. 95

4. In a shipping case, the combination of a body provided with notches in the upper edge of its rear wall, guides fixed within the case in alinement with said notches and projecting thereinto, and provided with transverse slots at their rear ends, a cover adapted to rest upon the body, and runners secured to and depending from the cover and slidably engaging the transverse slots in the guides. 105

5. In a shipping case, the combination of a body consisting of side and end pieces and vertically disposed metallic reinforcing plates extending around the ends of the side pieces and between the same and the ends of the end pieces and bearing against the inner faces of the end walls, fastening devices securing said reinforcing plates and said side and end pieces together, and a slidable cover having metallic reinforcing plates secured around its edges and resting upon and riding across the ends of the first-mentioned reinforcing plates. 115

6. In a bottle-shipping case, the combination of a body provided with a bottom having internally threaded openings therein, pins having reduced threaded lower ends 120

engaging the internally threaded openings in the bottom of the body, reinforcing strips extending longitudinally of the rows of openings in said bottom on the under side of 5 the same, and screws driven through the said reinforcing strips into the ends of the pins.

In testimony whereof I affix my signature, in presence of two witnesses.

GEO. G. ROBERTS.
